UNITED STATES PATENT OFFICE.

LIONEL DYCK, OF CHICAGO, ILLINOIS.

INTERNAL-COMBUSTION ENGINE.

Application filed December 29, 1925. Serial No. 78,081.

My invention relates to internal combustion engines, and the same has for its main object to improve generally on an engine construction of this class and to provide a 5 novel simplified construction which will be efficient in use and economical in manufacture. A further object is to provide a construction characterized by having two separate inlet fuel passages leading to each 10 cylinder, by having means for force-feeding the fuel through said passages, and by having means for force-exhausting the spent gases of combustion. Still a further object is to provide a structure of the character 15 specified in which provision is made to force-feed the fuel into the cylinder during the first half or portion of the compression stroke of the piston and to force-exhaust the spent gases during the second half or portion 20 of the power stroke of the piston.

Other objects will appear hereinafter.

The invention consists in the combinations and arrangements of parts hereinafter described and claimed.

25 The invention will be best understood by reference to the accompanying drawings forming a part of this specification, and in which,

Fig. 1 represents a top plan view of an 30 internal combustion engine produced in accordance with the present invention;

Fig. 2 represents a sectional detail showing the two exhaust ports for each cylinder, this view being taken on the line 2-2 of 35 Fig. 1;

Fig. 3 represents a cross section taken on the line 3-3 of Fig. 1; and,

Fig. 4 represents a cross section taken on the line 4-4 of Fig. 1.

40 In the drawings wherein for the purpose of illustration, is shown a preferred embodiment of the invention in a structure for use as a power plant for a motor vehicle, the numeral 5 represents in general an elongated 45 cylinder block provided with the cylinders 6 preferably arranged in line as shown, the cylinder block being suitably bolted or otherwise secured upon a suitable elongated crank casing 7 composed of an upper part 8 and a lower part 9 each flanged as at 10 for receiving the stay bolts 11.

With the rear end of the cylinder block 5 is associated a transmission gear case 12 of any suitable design; and with the front

end of said cylinder block is associated a gear 55 case 13 of a design suitable for containing a fly wheel 14, timing gears 15 and 16, and also a gearing train which will be more fully referred to hereinafter.

In the present form of construction, I have 60 illustrated the cylinder block as equipped with four cylinders in line; but it is to be understood that, in practice, I may employ as many cylinders as may be desired for the particular purpose in view and also that, 65 if desired, the cylinders may be arranged otherwise than in line. Inasmuch as the cylinders are alike in construction, it is thought that a detailed description of one will suffice for all. Arranged within each 70 cylinder for reciprocating movement is a suitable piston 17 having connection through a connecting rod 18 with a crank shaft 19 which is operatively mounted in the crank casing 7. Each of the cylinders is provided 75 with a suitable cylinder head 20 in which is a suitable water passage 21, communication between the water passages 21 of the several cylinders being insured by a connecting water conduit 22. Each cylinder head is 80 equipped with the usual spark plug 23 for igniting the fuel when compressed in the usual manner by the piston. Projecting outwardly from one side of each cylinder are two side bridges 24 and 25 arranged one 85 spaced over the other in vertical alinement. The upper bridge 24 is located adjacent the cylinder head 20 and is provided with a fuel inlet passage 26, and a fuel inlet port 27 which opens into an inlet passage 28 adjoining 90 the cylinder head and in communication with the interior of the cylinder at the point of highest compression. The lower bridge 25 has a fuel inlet opening 29 and an inlet port 30 in communication with an inlet passage 95 31 which opens into the cylinder at a point just above the mid-stroke of the piston. The fuel inlet passages 26 and 29 receive the fuel from inlet passages 32 and 33, respectively, which represent branches leading off from 100 a manifold passage 34 provided in a fuel manifold block 35 which is suitably bolted to the upper and lower bridges 24 and 25 of the cylinders. Preferably mounted in the manifold block 35 is a rotor 36 which draws 105 the fuel through the supply pipe 37 from the carburetor 38 and force-feeds it into the cylinder through the fuel inlet passages. From

what has been said, it will be understood that each cylinder is thus equipped with two fuel inlet passages, one located at the point of highest compression and the other located at a point just above the mid-stroke of the piston.

Suitable valves 39 and 40 are arranged on a push rod or tappet member 41 for controlling the respective fuel inlet ports 26 and 30. The push rod or tappet member 41 is suitably mounted for reciprocating movement in the bridges 24 and 25 and also in a block 42 arranged in the top 8 of the crank casing. On its lower end the push rod or tappet member 41 is furnished with a roller 43 adapted to bear directly against the periphery of a cam 44 fast on the timing shaft 45 carrying the timing gear 15. A spring 46 acts on the push rod or tappet member 41 so as to keep the valves 39 and 40 seated at all times except when the high point of the cam 44 engages the roller 43 to allow the admission of fuel into the cylinder. As illustrated in Fig. 4, the timing gear 15 is driven by a pinion 46 on the crank shaft 19. This entire arrangement is such that the valves 39 and 40 are unseated for the admission of fuel only during the first half of the compression stroke of the piston 17.

Each cylinder is also provided with upper and lower bridges 47 and 48, of which each upper bridge has an exhaust passage 49 into which the burnt gases or products of combustion enter through two exhaust ports 50 from an exhaust passage 51, the last named being under the cylinder head at the point of highest compression. Each exhaust passage 49 communicates with an exhaust passage 52 which represents a branch of the manifold passage 53 in manifold block 54 which is suitably bolted to the upper and lower bridges 47 and 48. Associated with the manifold block 54 is a rotor 55 which draws or sucks the burnt gases from the exhaust passage and discharges into an exhaust manifold 56. Each exhaust port 50 has a valve 57 co-operating therewith; and each valve 57 is mounted on a push rod or tappet member 58 suitably journaled for reciprocating movement in the upper and lower bridges and also in a block 59 arranged in the top 8 of the crank casing. Each push rod or tappet member 59 carries a roller 60 which turns on the periphery of cam 61 on the timing shaft 62 carrying timing gear 16 which is driven by the pinion 46 on the crank shaft.

This entire exhaust arrangement is such that the exhaust valves 57 are only opened for the discharge of the burnt gases during the second half of the power stroke of the piston. The cylinders are surrounded with suitable water passages 63 in communication with any suitable circulation system.

The rotors 36 and 55 are driven at a speed greatly in excess of the speed of the crank shaft. To this end, I preferably employ a chain of speed increasing gears which are operated by the fly-wheel gear 14. In the present construction the speed increasing gears comprise an arrangement of pinions 64 and gears 65 suitably arranged between the fly-wheel gear 14 and a center gear 66. The pinions and the gears comprising the chain are mounted on suitable shafts operatively arranged in a frame 67 secured in the gear casing. The center gear 66 drives the rotor 36 through gears 67 and 68; and it also drives the other rotor 55 through the gears 69 and 70.

From the foregoing description taken in connection with the accompanying drawings, it will be seen that I have provided an internal combustion engine which is very simple in construction and in operation and which can be cheaply manufactured and easily assembled.

In operation, the valves 39 and 40 are unseated for the admission of fuel into the cylinder during the first half of the compression stroke when the piston moves upwardly from its bottom terminal of movement to midway position as shown in Fig. 3, but they are closed for the compression of the admitted fuel during the second half of the compression stroke when the piston continues upwardly from midway position to its top terminal of movement. During the entire compression stroke of the piston from its bottom terminal of movement to its top terminal of movement, the exhaust valves 57 are closed. The moment the piston attains its top terminal of movement the compressed fuel is exploded by the spark of the spark plug. During the entire power stroke when the piston moves downwardly from the top terminal of movement to the bottom terminal of movement, the valves 39 and 40 are closed, but the exhaust valves 57 are unseated for the discharge of the spent gases of combustion during the second half of the power stroke when the piston moves downwardly from its midway position to its bottom terminal of movement. By this arrangement it will be evident that first the admission of the fuel and then the compression thereof takes place during the upward stroke of the piston, while first the firing and expansion of the exploded gas and then the exhaust of the products of combustion take place during the downward stroke of the piston. By providing two fuel inlets, one located just beyond the mid-upward-stroke of the piston and the other located adjacent the cylinder head, a full charge of fuel can be forced into the combustion chamber by the rapidly revolving rotor during the first half of the up-stroke of the piston; and similarly from the provision

of the two exhaust ports adjacent the cylinder head, the products of combustion can be effectually sucked from the cylinder by the suction rotor during the second half of the 5 down-stroke of the piston.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of 10 the appended claims.

Having described my invention, what I claim as new and desire to secure by Letters Patent is:

1. An internal combustion engine including a cylinder and a reciprocating piston therein; a pair of fuel inlet passages for the cylinder; one discharging thereto at the point of highest compression; the other discharging thereto at a point substantially 20 between the mid-stroke of the piston and the terminal of the compression stroke thereof; a rotor arranged to force-feed the fuel through said passages into the cylinder; and valves controlling the flow of fuel 25

through said passages, substantially as described. 30

2. An internal combustion engine including a cylinder with a reciprocating piston therein; a crank shaft having operative connection with the piston; a pair of inlet 35 passages leading to the cylinder, one opening thereto adjacent the cylinder head and the other opening thereto near the mid-stroke of the piston; an exhaust passage adjacent the cylinder head; a rotor arranged 40 to force-feed the fuel through the said inlet passages; a rotor arranged to force-exhaust the spent gases through said exhaust passage; timing devices operated from said crank shaft; tappet members under the control of said timing devices provided with valves controlling each of said inlet passages and said outlet passage; said timing devices being arranged to open both the fuel 45 inlet valves during the first half of the compression strokes of the piston and to open the exhaust valve during the second half of the power strokes thereof, substantially as described.

In testimony whereof I have signed my 50 name to this specification.

LIONEL DYCK.
